(57) **CLAIM**

The ornamental design for a pour over coffee machine as shown and described.

DESCRIPTION

FIG. 1 is a front right perspective view of a pour over coffee machine showing my new design;

FIG. 2 is a rear left perspective view thereof;

FIG. 3 is a front elevation view thereof;

FIG. 4 is a top plan view thereof; and,

FIG. 5 is a right side elevation view thereof.

The evenly broken lines depict unclaimed portions of the pour over coffee machine or environmental structure. The broken lines form no part of the claimed design.

1 Claim, 5 Drawing Sheets
